UNITED STATES PATENT OFFICE.

ALNEY G. NEWMAN, OF WAUNETA, KANSAS.

DESIGN FOR A SUBSOIL ATTACHMENT FOR CORN OR COTTON LISTERS.

SPECIFICATION forming part of Design No. 33,042, dated July 31, 1900.

Application filed July 5, 1900. Serial No. 22,634. Term of patent 14 years.

To all whom it may concern:

Be it known that I, ALNEY G. NEWMAN, a citizen of the United States, residing at Wau-
neta, in the county of Chautauqua and State
5 of Kansas, have invented and produced a cer-
tain new and original Design for Subsoil At-
tachments for Corn or Cotton Listers; and I
do declare the following to be a full, clear, and
exact description of the invention, such as
10 will enable others skilled in the art to which
it appertains to make and use the same.

The invention relates to a new and original
design for a subsoil attachment for corn or
cotton listers; and it consists of a design of
15 the shape and configuration shown in the ac-
companying drawings, in which—

Figure 1 is a perspective view. Fig. 2 is a
side elevation, and Fig. 3 is a front elevation.

The leading feature of the design comprises

the horizontal body portion 1, provided with 20
vertical sides 2 and outwardly-projecting
wings 3, which have their front ends beveled
from their point of intersection with the side
pieces rearwardly, while the side pieces 2
have their front ends from their point of in- 25
tersection with the wings beveled upwardly
and rearwardly.

What I claim is—

The design for a subsoil attachment for corn
or cotton listers, as herein shown and de- 30
scribed.

In testimony whereof I have hereunto set
my hand in presence of two subscribing wit-
nesses.

ALNEY G. NEWMAN.
